UNITED STATES PATENT OFFICE.

WARREN TRAVELL, OF NEW YORK, N. Y.

ROPE-GRIP.

1,397,259.

Specification of Letters Patent. Patented Nov. 15, 1921.

Application filed May 8, 1919. Serial No. 295,758.

To all whom it may concern:

Be it known that I, WARREN TRAVELL, a citizen of the United States, and resident of city of New York, in the county of New York and State of New York, have invented 5 certain new and useful Improvements in Rope-Grips, of which the following is a specification.

This invention relates in general to improvements in rope clamping devices.

More particularly it relates to that class of rope-grips, which utilizes the frictional resistance caused by pressure of gripping surfaces upon the rope to attain the clamping 15 action.

The objects of the invention are to produce an effective means for arresting the traveling motion of ropes in hoisting and transporting machinery at the will of the 20 operator in a more efficient way than heretofore.

In order to show how the device may be used and also to explain more clearly its mode of operation, the description to follow 25 should be read in conjunction with my U. S. Letters Patent No. 1,184,051, hoisting and transporting mechanism, issued May 23rd, 1916. It is in effect an improvement over the rope grip shown in Figures 4 and 5, and 30 fully described as to its function and operation, but not specifically claimed under said Letters Patent.

The accompanying drawing illustrates only one way in which I attain the aim of 35 my invention, but it will be understood that other equivalent means may be used and that either hand-power, electrical or mechanical means may be utilized as prime-mover in producing the pressure and frictional resistance necessary to prevent the 40 motion of the rope.

With the aforesaid objects in view, the invention consists of the improvements, novel construction, arrangement and combination of elements hereinafter described, 45 defined in subjoined claims and illustrated in the annexed drawings, wherein like elements are designated by the same reference characters throughout the several views.

In the said drawings,

Fig. 1 is an elevation of the rope grip, wherein the ropes are shown broken and the two main parts brought closer together than will be practical in actual operation,

Fig. 2 is a sectional elevation on line 2—2 of Fig. 1,

Fig. 3 is a section on line 3—3 of Fig. 1 and

Fig. 4 is a section on line 4—4 of Fig. 3.

As shown in the said figures, the device 60 may be said to consist essentially of adjustable toggles operated by means of rope-leverage on sheaves.

In the various views ropes 1 and 2 represent the counterweight rope and traveling 65 rope, corresponding to ropes 21 and 23 respectively, which may be alternately clamped as shown in Figs. 3, 4 and 5 of the above mentioned reference patent. For the purpose of controlling the motion of said 70 ropes, the sheaves 3 and 4 are operatively connected by a rope 5, preferably dead ended or clamped on said sheaves so as to prevent slipping. A hand-lever 6 with spring lock and the sheave 3 revolve together on 75 pin 7, said pin being supported on bracket 8 and the quadrant 9. In operating the hand-lever 6, sheave 3 will rotate sheave 4 by means of rope 5, causing gears 10, 11 and 12 to rotate their respective shafts upon 80 which are rigidly fixed the toggle-wheels 13, 14 and 15. In the recesses of the toggle-wheels are pivoted the clamps proper 16, connected in pairs by means of guide-links 17, to insure parallel motion and uniform 85 pressure on the rope. The clamps are grooved on both sides to fit the rope and are reversible, thus doubling the allowable wear. The toggle-wheels are provided with a series 90 of holes, arranged to permit of adjustment for different sizes of rope or to compensate for wear of the clamps. The upper half of the device is held together as a unit by means of a frame 18, which may be bolted to any convenient part of the structure. 95

It will readily be seen that either of ropes 1 or 2 may be clamped by throwing the hand-lever 6 to the left or right, or both ropes may be free to travel if the lever be left in an intermediate position.

As illustrated in Figs. 1, 2 and 4 the ropes are assumed to travel in a downward direction under load, as shown by arrows. The clamps should be so adjusted that when gripping the rope, the pins connecting the 105 clamps proper to the toggle-wheels 13, 14 and 15 will not be permitted to descend below a horizontal line through the center line of the shafts carrying the toggle-wheels.

It will be understood that changes in 110 form, arrangement, sizes, proportions and details of the device may be made without

departing from the scope of the invention as defined by the appended claims, also that any other means than handpower may be used as prime-mover for actuating the grip.

5 Having described my invention, what I desire to secure by Letters Patent and claim is:—

1. A double rope grip comprising friction jaws; toggle-wheels whereon said friction jaws are suitably mounted, for varying the pressure between said friction jaws and the ropes and adapted to positively release either one of two ropes when gripping the other rope; and means for applying power 10 to and controlling the motion of said toggle wheels.

2. A double rope grip comprising two pairs of friction jaws; toggle wheels whereon said friction jaws are suitably mounted; means for maintaining said friction jaws parallel with the ropes; and means for actuating said toggle wheels whereby clamping pressure is applied through either pair of said friction jaws to its included rope 20 and whereby at the same time the other rope is released from the clamping pressure of its pair of friction jaws.

3. In a double rope grip, the combination of two pairs of friction jaws; toggle 30 wheels whereon said friction jaws are suitably mounted; gearing whereby said toggle wheels are actuated; a lever; and a system of links connecting said lever with said gearing, the whole constituting a means for applying gripping pressure on the rope passing between each pair of jaws and for positively releasing from gripping pressure either rope when such pressure is applied to the other rope.

40 4. In a rope grip, the combination of two pairs of friction jaws; toggle members whereon said friction jaws are mounted; means for maintaining each pair of friction jaws parallel with its engaged rope; gearing operatively connecting said toggle members; a lever; and a rope operatively connecting said lever with said gearing, the whole constituting a means for applying

gripping pressure between the pairs of friction jaws and their respective ropes and for 50 positively releasing from such gripping pressure either of the two ropes when the other rope is gripped.

5. In a double rope grip, the combination of two pairs of friction jaws, each pair of which is adapted to apply gripping pressure to a rope which passes between its jaws; three disks, upon which the friction jaws are pivotally and eccentrically mounted so as to obtain a toggle action in the application of pressure to the ropes; shafts to which the disks are attached; a supporting frame; means whereby either grip is thrown out of operation whenever the other grip is put in operation; and means for applying 60 pressure between the grips and their respective ropes.

6. In a double rope grip, the combination of two pairs of grip jaws; three rotating members on which said jaws are mounted eccentrically; means for gearing these rotating members together so that when the jaws of one pair are coming together, the jaws of the other pair are separating; and actuating means for rotating these members, whereby 75 gripping pressure is exerted between either pair of jaws and an included rope.

7. In a double rope grip, the combination of two pairs of grip jaws; rotating members on which said jaws are mounted eccentrically; means for gearing these rotating members together so that when the jaws of one pair are coming together, the jaws of the other pair are separating; sheaves operatively connected to said gearing; a lever; 80 and rope passing around said sheaves, and operatively connecting them to said lever, whereby movement of the lever rotates these members and gripping pressure is exerted between either pair of jaws and an included 90 rope.

Signed at New York city in the county of New York and State of New York this 27th day of February, A. D. 1919.

WARREN TRAVELL.
